J. WADE, S. J. MARKIN AND H. A. DU PREY,
DOOR OPENING AND CLOSING DEVICE.
APPLICATION FILED OCT. 13, 1919.

1,347,193.

Patented July 20, 1920.

UNITED STATES PATENT OFFICE.

JOHN WADE, OF ST. PAUL, AND SIDNEY J. MARKIN AND HARTWELL A. DU PREY, OF MINNEAPOLIS, MINNESOTA; SAID MARKIN ASSIGNOR TO SAID WADE AND SAID DU PREY.

DOOR OPENING AND CLOSING DEVICE.

1,347,193.

Specification of Letters Patent.

Patented July 20, 1920.

Application filed October 13, 1919. Serial No. 330,328.

To all whom it may concern:

Be it known that we, JOHN WADE, SIDNEY J. MARKIN, and HARTWELL A. DU PREY, citizens of the United States, the said JOHN WADE residing at St. Paul, county of Ramsey, and State of Minnesota, SIDNEY J. MARKIN residing at Minneapolis, county of Hennepin, and State of Minnesota, and HARTWELL A. DU PREY residing at Minneapolis, county of Hennepin, and State of Minnesota, have invented new and useful Improvements in Door Opening and Closing Devices, of which the following is a specification.

15 Our invention relates to improvements in door opening and closing devices.

Its object is to provide a simple, durable and inexpensive device for opening and closing a hinged door having a latch thereon, said device including mechanism for withdrawing the latch and thus securing the same while the door is open.

20 More specifically it is our object to provide an improved device of this nature for opening and closing the door of a passenger vehicle from a position near the attendant's station, said device including latch withholding means, which remain operative when the door is open to prevent injury by 25 the latch to the persons or clothing of passengers boarding or leaving the vehicle.

We attain these and other objects by the construction shown in the accompanying drawings, which illustrate an embodiment 30 of our invention.

In the drawings, illustrating our preferred mechanism, Figures 1 and 2 are fragmentary views, respectively in plan and in elevation, Fig. 1 being taken on the line 1—1 of Fig. 2 and Fig. 2 on the line 2—2 of Fig. 1. These views show particularly a door and mechanism for swinging the same. Fig. 3 is a fragmentary view in elevation taken on the line 3—3 of Fig. 1 and shows a door 45 and latch therefor, together with the latch operating mechanism. The inner panels of the door are here omitted and a portion of the latch slide is broken away for the sake of clearness.

50 Referring to the drawings, we have indicated a support 10, a side-wall 11 and a door 12 mounted on the side-wall by means of hinges 13. A latch 14 on the door 12 includes a body 15 with a bolt 16 slidable 55 therein and having a spring 17 for yield-

ingly holding the same in a latch opening (not shown) in the side-wall. Revolubly journaled in a bearing 18 on the support 10 is an upright operating shaft 19. This shaft is braced near its upper end by a suitably anchored bracket 20. At the top of said shaft is a crank 21, which is turned by an attendant to open and close the door 12. An arm 22 near the lower end of the shaft is pivotally connected with one end of a thrust-lever 23, the opposite end of said lever being formed with a slot 24 therein and a cam surface 25 thereon. Said end of the thrust-lever is connected with a bracket 26, on the door 12, by means of a pin 27 passing through said bracket 26 and slot 24. A bell crank 28 is mounted upon the door 12 in position with the lower arm 29 thereof adjacent to the cam surface 25 on said thrust-lever. The upper arm 30 of said bell crank 28 is connected by a rod 31 with the arm 32 of a second bell crank 33 on the door 12. The arm 34 of said second bell crank 33 is connected by a rod 35 with an extension 36 on the bolt 16 of the latch 14. Initial turning of the hand crank 21 to push the lever 23, first causes the cam surface 25 to strike the arm 29 of the bell crank 28, thus withdrawing the latch bolt 16. Continued movement of said crank, brings the inner end of the slot 24 into contact with the pin 27, in the bracket 26, on the door 12 and causes the door to open. Reverse movement of the crank 21, first carries the outer end of the slot 24 into contact with said pin and continued movement of said crank pulls the door into closed position. In all positions of the door, except when closed, the latch bolt 16 is withdrawn, due to the engagement of the cam surface 25 with the arm 29 of the bell crank 28. This position of the latch obviates injury thereby to the persons or clothing of passengers boarding or leaving the vehicle. Suitable sealing panels 37 on the door 12 cover the latch operating mechanism. It will be observed that the door 12 cannot be opened by unauthorized persons, since the sole means for opening said door lies in the crank 21 and connections thereto, said crank being located within reach of the attendant.

Changes in the specific form of our invention as herein disclosed, may be made within the scope of what is claimed without departing from the spirit of our invention.

Having described our invention, what we claim as new and desire to protect by Letters Patent is:

1. In a device of the class described, the combination with a hinged door having a latch thereon, of a crank, a thrust-lever pivotally attached at one end thereto and having a pivotal and limited slidable connection at its other end with said door, a cam surface on said latter end of said thrust-lever and mechanism connected with said latch and actuated by said cam surface for withdrawing the latch and withholding the same during the swing of the door.
- 15 2. In a device of the class described, the combination with a hinged door having a spring pressed latch thereon, a thrust-lever attached to said door and adapted to open and close the same, means for operating said thrust-lever, latch withdrawing mechanism actuated by the thrust-lever, said mechanism being designed to withdraw the latch upon the initial movement of the thrust-lever, to open the door, and to hold said latch in such 25 position until the door is again closed.

3. In a device of the class described, the combination with a hinged door having a spring pressed latch thereon, of an operating shaft, a hand crank and an arm thereon, a thrust-lever pivotally attached at one end 30 to said arm and being supplied at its other extremity with an enlargement formed with a slot therein and a cam surface thereon, a bracket on the door, a pin in said bracket passing through the slot in said thrust-lever, 35 a bell crank on the door, one arm thereof being located adjacent to the cam surface on the thrust-lever, connecting means joining the other arm of said bell crank with said latch, said cam surface being adapted, upon 40 the initial thrust of the lever, to strike the bell crank and withdraw the latch and, further, to so hold said latch until the door is again closed.

In testimony whereof, we have signed our 45 names to this specification.

JOHN WADE.
SIDNEY J. MARKIN.
HARTWELL A. DU PREY.
